UNITED STATES PATENT OFFICE.

SAM F. KLOHS, OF CHICAGO, ILLINOIS, ASSIGNOR TO T. W. SNOW CONSTRUCTION COMPANY, OF CHICAGO, ILLINOIS.

HOOP-SECURING MEANS.

1,070,613.

Specification of Letters Patent. Patented Aug. 19, 1913.

Application filed September 17, 1912. Serial No. 720,743.

To all whom it may concern:

Be it known that I, SAM F. KLOHS, a citizen of the United States, residing at Chicago, in the county of Cook and State of Illinois, have invented a new and useful Hoop-Securing Means, of which the following is a specification.

My invention relates to improvements in the means, commonly known as hoop-lugs, for securing hoops about a tank or the like, by drawing the ends of the hoops together and thus binding the hoops about the tank.

Heretofore, so far as I am aware, the form of securing means employed have been such as to require the ends of the hoops to be bent into interlocking engagement with the lugs after applying the latter thereto and under ordinary conditions, after the hoops have been applied to the tanks, this procedure presenting manifest objections.

My object is to provide a construction of securing means for the purpose above stated whereby bending of the ends of the hoops into loop-form, after the lug-members are applied thereto, is avoided in the act of interlocking the lug-members with the hoops, thereby expediting the operation of applying the hoops to tanks and minimizing the inconvenience and expense attending this operation.

Referring to the accompanying drawings—Figure 1 is a broken horizontal section taken through a wooden tank and showing my improved hoop-securing means in plan. Fig. 2 is a horizontal section taken through one of the members of my improved securing means, the section being taken at the line 2 on Fig. 3 and viewed in the direction of the arrow. Fig. 3 is a view in side elevation of the member shown in Fig. 2. Fig. 4 is an end view of the member shown in Fig. 3. Fig. 5 is a view similar to Fig. 1 of another form in which my invention may be embodied. Fig. 6 is a broken horizontal sectional view of one of the members of the securing-means shown in Fig. 5, the section being taken at the line 6 on Fig. 7 and viewed in the direction of the arrow. Fig. 7 is a view in side elevation of the member shown in Fig. 6; and Fig. 8, a perspective view showing the form into which the ends of the hoops are bent for assembling with the lug-members.

A portion of a wooden reservoir, or tank, is represented at 9 and as is usual in con-

structions of this character would be provided with a plurality of hoops for holding its wood-sections together, a portion of one of the hoops being represented at 10.

Referring to Figs. 1 to 4, inclusive, the 60 hoop 10 is shown as secured in position about the tank 9 by my improved securing means, which comprise, in the preferred form, a pair of similar securing-members 11 adapted to interlock with the ends of the 65 hoop which are preferably reversely bent to form hooks 12 (Fig. 8), and in such interlocking engagement with the hoops be secured together. Each of the members 11 is formed of relatively offset sections 13 and 70 14 with an opening 15 between their adjacent ends of sufficient size to permit a hook-end 12 of the hoop to be inserted therethrough to position the latter at its hook-end in the rear of the section 14 and permit 75 it to be moved to a position in which it will hook over the outer end of the section 14 and thus interlock therewith, as illustrated in Fig. 2. As I prefer to form the members 11 each is recessed along its front side as 80 represented at 16 to form the section 13 and side sections 17 and 18, and recessed along its rear side as represented 19 to form the offset section 14 with the opening 15 communicating with the recesses 16 and 19, the 85 member 11 being formed with a socket 20, one of the walls of which is the section 14. Each member 11 at one end thereof is provided with flanges 21 which are integral with bosses 22 extending above and below 90 the section 13 and containing holes 23 for receiving tightening devices hereinafter described.

In employing my improved securing means the ends of the hoop are first bent 95 to form the hooks 12 and the hoop then assembled with a pair of the members 11 by interlocking the hoop-ends with the members 11, as hereinbefore described, and as shown in Figs. 1 and 2. The hoop is then positioned on the tank and bolts 24, or the like, then inserted into the holes 23 of the opposed members 11 and the nuts 25 on said bolts tightened to draw the members 11 together for producing the desired tightness 100 105 of fit of the hoop about the tank.

The construction illustrated in Figs. 5 to 7, inclusive, which shows a desirable form of construction where it is desired that but one bolt 24 be employed, is the same in construc- 110

tion and operation as that of the preceding figures excepting, that instead of providing two, upper and lower, bosses on each member, a single apertured boss 26 is provided, 5 these bosses being formed on the front sides of the members 11 and bridging the side sections 17 and 18 and connected with the section 14.

10 While I have illustrated and described certain forms in which my invention may be embodied, I do not wish to be understood as intending to limit it to embodiment in such forms, as it may be embodied in many other forms within the spirit of my invention.

15 What I claim as new and desire to secure by Letters Patent is—

1. Hoop-securing means formed of a pair of members, each formed with spaced sections and adapted to permit a hoop having 20 an end preliminarily deflected to form a hook, to be assembled with said members and to be interlocked at its hooked end with one of said sections and extend at its deflected portion between said sections without flexing 25 or bending said deflected portion.

2. Hoop-securing means formed of a pair of members, each formed with sections spaced apart at their adjacent ends to afford an opening therebetween for the insertion 30 therethrough of the entire hooked end of a hoop for interlockingly engaging at its deflected portion with one of said sections.

3. Hoop-securing means formed of a pair of members, each formed with relatively-offset sections spaced apart at their adjacent ends to afford an opening therebetween for the insertion therethrough of the entire hooked end of a hoop for interlockingly engaging at its deflected portion with one of 35 said sections.

4. Hoop-securing means formed of a pair

of members, each formed with relatively-offset sections spaced apart at their adjacent ends and arranged in non-overlapping condition to afford an opening therebetween for 45 the insertion therethrough of the entire hooked end of a hoop for interlockingly engaging at its deflected portion with one of said sections.

5. Hoop-securing means formed of a pair 50 of members, each containing communicating recesses in its opposite sides to afford relatively-offset non-overlapping sections spaced apart at their adjacent ends to afford an opening therebetween for the insertion therethrough of the entire hooked end of a hoop 55 for interlockingly engaging at its deflected portion with one of said sections.

6. The combination with a hoop having its 60 ends preliminarily deflected to form hooks, of securing means for said hoop comprising a pair of members containing openings for insertion therethrough of the entire hooked ends of the hoop, means on said members for interlocking with the deflected portions of 65 said hoop, and means on said members for drawing the latter toward each other, for the purpose set forth.

7. A hoop-lug provided with sections disposed in different planes to render them offset relative to each other and spaced apart at their adjacent ends to afford an opening therebetween for the insertion therethrough of the entire hooked end of a hoop for interlockingly engaging at its deflected portion 75 with one of said sections, the other of said sections forming a seat for the hoop intermediate the ends of the latter.

SAM F. KLOHS.
